(57) **CLAIM**

The ornamental design for a container for measuring electrical characteristics, as shown and described.

DESCRIPTION

FIG. 1 is a perspective view of a first embodiment of a container for measuring electrical characteristics showing our new design wherein the container is transparent; FIG. 2 is a left side elevational view thereof; FIG. 3 is a perspective view of a second embodiment of a container for measuring electrical characteristics showing our new design;

FIG. 4 is a front elevational view thereof; and, FIG. 5 is a cross sectional view thereof cut along the line 5-5 of FIGS. 1 and 3.

Broken lines illustrate unclaimed portions of the container for measuring electrical characteristics and form no part of the claimed design. Dot-dash broken lines illustrating boundaries of the claimed design form no part of the claimed design.
